UNITED STATES PATENT OFFICE.

WILLIAM N. McCOMB, OF NEW YORK, N. Y.

DESIGN FOR A CHARACTER-PLATE FOR ILLUMINATED ADVERTISING-SIGNS.

No. 39,976.

Specification for Design.

Patented May 4, 1909.

Application filed January 19, 1909. Serial No. 473,198. Term of patent 14 years.

To all whom it may concern:

Be it known that I, WILLIAM N. McCOMB, a citizen of the United States, residing at New York, in the county and State of New York, have invented a new, original, and ornamental Design for a Set of Character-Plates for Illuminated Advertising-Signs, of which the following is a specification, reference being had to the accompanying drawing, forming part thereof, and which illustrates in front elevation the character-plates

constituting a set and embodying my new design.

What I claim is:

The ornamental design for a set of character plates for illuminated advertising signs, as shown.

WILLIAM N. McCOMB.
